UNITED STATES PATENT OFFICE.

HENRY ARNOLD, OF MELLEN, WISCONSIN, ASSIGNOR OF ONE-HALF TO G. H. HAGEN, OF MELLEN, WISCONSIN.

WINDOW-SHADE.

1,326,012.

Specification of Letters Patent. Patented Dec. 23, 1919.

Application filed September 24, 1919. Serial No. 325,891.

To all whom it may concern:

Be it known that I, HENRY ARNOLD, a citizen of the United States, residing at Mellen, in the county of Ashland and State 5 of Wisconsin, have invented new and useful Improvements in Window-Shades, of which the following is a specification.

This invention relates to window shades and more particularly to the class of adjustable roller shades for windows, doors, or the like.

The primary object of the invention is the provision of a shade of this character wherein the same can be readily raised or lowered relative to the window frames and locked in its adjusted position, the shade being of novel construction so as to exclude light, dust, dirt, and the like when completely closed with respect to the window 20 frame.

Another object is the provision of a shade of this character wherein the same will be held smooth in its adjusted position and can be readily raised and lowered as the occasion requires.

A further object of the invention is the provision of a shade of this character wherein the lock for holding the same in adjusted position is of novel form to permit 30 the shade to be pulled down or lowered, yet it will be locked against raising movement until the lock is released.

A still further object of the invention is the provision of a shade of this character 35 which is extremely simple in construction, thoroughly reliable and efficient in its purpose, strong, durable, and inexpensive in manufacture and installation.

With these and other objects in view, the 40 invention consists in the features of construction, combination of elements, and arrangements of parts as will be hereinafter fully described, illustrated in the accompanying drawings, and pointed out in the 45 claim hereunto appended.

In the accompanying drawings:

Figure 1 is an elevation of a window frame with a shade constructed in accordance with the invention applied.

Fig. 2 is an enlarged sectional view on the line 2--2 of Fig. 1,

Fig. 3 is a sectional view on the line 3--3 of Fig. 1, and

Fig. 4 is a cross sectional view on the line 4--4 of Fig. 3.

Referring more particularly to the drawing, A designates generally a window frame which is of the ordinary well known construction having the usual sliding sash B and upon this window frame at the inner side 60 thereof is mounted the adjustable shade hereinafter fully described.

The adjustable shade comprises a spring winding roller 5 of the usual construction having fixed thereto one end of a flexible 65 shade 6 adapted to be wound thereon and unwound therefrom in the raising and lowering of the said shade, the roller 5 being journaled in brackets 7 which are of the ordinary well known construction fixed to 70 the window frame at the desired point near the head thereof. Secured to the inner edges of the vertical stiles of the window frames are vertical guides each comprising a pair of sections 8 which serve as companions and 75

are cut to form a longitudinal guide bore 9 therebetween, and a slot 10 communicating with the bore and opening through the outer edge of said guide while within these bores 9 on the guides are stationarily mounted vertical guide rods 11 which are held in any suitable manner centrally located within the bore 9 which are of increased internal diameter with respect to the cross sectional area of the guide rods 11 and slideable upon 80 these guide rods are longitudinal edge casements 12 formed on the shade 6, the rods 11 being extended from the base of the window frame A to a point close to the position of the roller 5 for the shade 6 while the guides 85 including the sections 8 are coextensive with these rods and by reason of the particular slideable connection of the flexible shade 6 with the rods and working interior of the guides the said shade when drawn or pulled 90 down will exclude dust, dirt or the like from an entrance through the window. Furthermore, when the shade is pulled down, light 95 will be excluded through the window and also a maximum amount of air will be shut 100 out from entering the inclosure through the window, as will be obvious.

Carried at the lower end of the shade 6 is a reinforcing bar 13 which is formed with bifurcated ends 14 in which are journaled friction rollers 15, the periphery of each being engaged with the guide rod 11 next thereto so that the shade 6 when adjusted will move uniformly and be held in smooth condition. The rollers are journaled on pins 15^a.

- 10 Formed at intervals in the outer edges of the guides are notches or sockets 15' while suitably mounted in the bar 13 are spring-held slideable latch pins 16 having beveled ends 17 so that the same will ride out of 15 the notches 15' when entering the same on the pulling down of the shade 6 or will lock in the said notches or sockets 15' to prevent the raising of the shade thereby locking the same in adjusted position. Each latch pin 20 16 has a slot 16^a slidably engaging the adjacent pivot pin 15^a.

Mounted for vertical sliding movement on the reinforcing bar 13 centrally thereof is a latch releasing hand-hold 18 to the base 25 members 19 of which are fixed flexible pull cables 20, the same being also connected to the latch pins 16. The leg or base members operate within vertical slots 19^a. This hand-hold 18, when moved in one direction, re-

leases the latch pin 16 for the free adjustment of the shade 6 to permit either the raising or lowering thereof relative to the window frame, the bar 13 being formed with guide grooves 21 for accommodating the cables 20 which are acted upon by the hand-hold hereinbefore described.

From the foregoing it is thought that the construction and manner of use of the window shade will be clearly understood. Therefore a more extended explanation has 40 been omitted.

Having thus described my invention, I claim:

In combination with a window frame and a shade mounted on a roller, guide members 45 at the sides of the window frame provided with notches, a bar at the free end of the shade, rollers pivoted on pins at the ends of said bar and engaging said guides, latch members slideable on said pins and spring 50 pressed into engagement with said notches, a handle member mounted for vertical movement on said bar, and flexible members connected with said handle member and said latch members.

In testimony whereof I affix my signature.

HENRY ARNOLD.
